CAN HOLDER

Claude Cummins Freeman, Fort Worth, Tex., assignor to Container Corporation of America, Chicago, Ill., a corporation of Delaware

Application November 15, 1950, Serial No. 195,853

7 Claims. (Cl. 229—87)

1

The present invention relates to a one-piece collapsible can holder and is particularly concerned with a paperboard can holder that is adapted to hold at least two cans of different sizes in a unitary package.

It is an object of this invention to provide a simple inexpensive glued blank that may be shipped in flat condition and may be easily and quickly set up to hold a row of at least two cans of different sizes.

It is a further object of this invention to provide a can holder having its top and bottom surfaces parallel, even though the cans packaged therein are of different heights, and so constructed as to provide sufficient rigidity to permit a plurality of the packaged units to be stacked uniformly without damage to any of the can holders.

Other and further objects and advantages of the invention will become apparent upon reading the following description, taken in conjunction with the accompanying drawing showing a preferred illustrative embodiment of the invention, in which:

Fig. 1 is a perspective view of a can holder embodying the invention, showing the holder applied to a pair of cans of different sizes;

Fig. 2 is a perspective view similar to Fig. 1, with the cans removed and showing the can-retaining flaps interiorly of the holder in dotted lines;

Fig. 3 is an end elevation of the can holder with the cans removed;

Fig. 4 is a cross-sectional view, taken generally along the line 4—4 of Fig. 3, but showing the cans in dotted lines;

Fig. 5 is a perspective view of the can holder in open set-up position with the can-retaining flaps extended;

Fig. 6 is a plan view of the blank from which the can holder is made; and

Fig. 7 is an elevational view showing the holder in collapsed flat condition for shipment.

Referring to the drawings, the reference numeral 2 indicates a top wall panel having a side wall panel 3 extending from one edge thereof and another side wall panel 4 extending from the opposite edge thereof. A fold line 5 extends between top wall panel 2 and side wall panel 3, and another fold line 6 extends between the top wall panel 2 and side wall panel 4. It will be noted that the fold lines 5 and 6 are not parallel to each other. This arrangement is to make the top wall wider at one end than at the other to receive a can 7 of larger diameter than the can 8 secured in the other end of the can holder. If both cans to be packaged in the holder are

2

of the same diameter, fold lines 5 and 6 will be formed along parallel lines so that the can holder will be of uniform width.

A fold line 9 extends between side wall panel 4 and a bottom wall panel 10. The bottom wall panel 10 and top wall panel 2 are the same size. A glue flap 11, foldable along fold line 12, extends from the edge of bottom wall panel 10 opposite the fold line 9. The bottom wall panel 10 has a pair of can-retaining flaps 13 and 14 extending from its opposite ends. The flap 13 is foldable along line 15 and the flap 14 is foldable along line 16. Flap 14 is larger than flap 13 because in the illustrated embodiment can 7 has a larger diameter than can 8.

The top wall panel 2 has a can-retaining flap 17 extending from one end. Flap 17 is the same size as flap 14 and is foldable along line 18. Flaps 14 and 17 are positioned at corresponding ends of top and bottom wall panels 10 and 12, respectively, and cooperate to engage the inner portion of the flanges 19 and 20 or chimes of can 7 to hold the can securely in the holder. The can may be inserted into the holder easily with the flaps 14 and 17 folded inwardly against the inner surfaces of bottom wall panel 10 and top wall panel 2, respectively. However, the resilience of the paperboard from which the holder is made gives the flaps a tendency to spring away from the top and bottom walls so that after the can has been inserted far enough to allow the flanges 19 and 20 to clear the edges 21 and 22 of the flaps 14 and 17, respectively, any attempt to remove the can 7 will cause the flanges to engage and abut against the edges of the flaps. In the embodiment illustrated, the edges 21 and 22 are shaped arcuately to conform to the flange of the can 7, but other shapes may be employed which similarly engage the can flanges. Accordingly, it is impossible for the can 7 to become accidentally displaced from the can holder.

The end of the can holder opposite the flaps 14 and 17 is arranged to receive the can 8 which is of less height than the can 7. The flap 13 is arcuately shaped and engages the inner portion of flange or chime 23 at the bottom of the can in the same manner that the flaps 14 and 17 engage the flanges of can 7. In order to keep the top wall panel 2 parallel to the bottom wall panel 10 and still have a can-retaining flap 24 engage the flange or chime 25 on the upper edge of the can 8, the flap 24 is hinged to an intermediate flap 26 along the fold line 27. The outer edge of flap 24 is also shaped arcuately to conform to the flange of can 8. The intermediate

flap 26 is hinged to the end of top wall panel 2 along the fold line 28.

A pair of reinforcing flaps 29 and 30 are hinged to corresponding upper edges of side wall panels 3 and 4 along fold lines 31 and 32, respectively, so as to fold inside and adjacent to the intermediate flap 26 when the latter is folded along its fold line 28. The flap 24 is provided with a pair of tabs 33 and 34 foldable along lines 35 and 36, respectively, so that the edge 37 of tab 33 abuts the inner surface of flap 29, and the corresponding edge 38 of tab 34 abuts the inner surface of flap 30 when the flap 24 is in position to engage the inner portion of flange or chime 25. The edge 39 of flap 29 which is adjacent the fold line 27 is recessed, as indicated at 40, and the corresponding edge 41 of flap 30 is similarly recessed, as indicated at 42, so that when flap 24 is folded along fold line 27 it will be substantially flush with the edges 39 and 41 of the reinforcing flaps 29 and 30. This arrangement provides a firm support for the top of the can 8, and the intermediate flap 26, together with the reinforcing flaps 29 and 30, which are held in juxtaposed relation by tabs 33 and 34, form a rigid support strong enough to support the weight of superimposed objects without collapse. This enables a plurality of units comprising cans held in the can holder of the present invention to be stacked one upon another in neat rows on the shelf of the dealer.

A fold line 43 is formed medially of the top portion of the can holder and extends from the outer edge of flap 17 to the outer edge of flap 24. A corresponding fold line 44 is provided on the bottom extending from the outer edge of flap 13 to the outer edge of flap 14. The fold lines 43 and 44 permit the can holder to be folded flat, as shown in Fig. 7, after the glue flap 11 has been adhered to the free edge of side wall panel 3, so that the holders can be shipped in flat condition. When the can holders are dimensioned for use with cans of the same diameter although of different height the fold lines 43 and 44 are not necessary because the fold lines 5, 6, 9 and 12 are then parallel to each other, and the can holders may be folded flat along these fold lines.

While the present description sets forth a preferred embodiment of the invention, many changes may be made in the construction without departing from the spirit of the invention, and it is therefore desired that the present embodiment be considered in all respects as illustrative, and not restrictive, reference being had to the appended claims rather than to the foregoing description to indicate the scope of the invention.

I claim:

1. A can holder for a row of cans, said row including at least two cans of different heights at its ends, comprising top and bottom wall panels connected by a pair of side wall panels, means integral with the bottom wall panel foldable to engage the inner portions of the chimes of each of the said end cans positioned in the can holder, means integral with the top wall panel at one end and foldable to engage the inner portion of the top chime of the taller of said end cans, an end wall forming flap extending downwardly from and hinged to the other end of the top wall panel, the vertical extent of said end wall forming flap being substantially equal to the difference in height between said two cans of different height, and a can retainer flap hinged to the end wall forming flap and engageable with the inner

portion of the top chime of the shorter of said end cans, the last mentioned flap being positioned in a plane substantially lower than the plane of the top wall panel.

2. A can holder for a row of cans, said row including at least two cans of different heights at its ends, comprising top and bottom wall panels connected by a pair of side wall panels, a flap integral with the bottom wall panel at each end thereof and foldable to engage the inner portions of the chimes of said end cans respectively when the latter are positioned in the can holder, a flap integral with the top wall panel at one end and foldable to engage the inner portion of the top chime of the taller of said end cans, an end wall forming flap extending vertically downwardly from and hinged to the other end of the top wall panel, and a can retainer flap hinged to the end wall forming flap and foldable inwardly of the holder and engageable with the inner portion of the top chime of the shorter of said end cans, the last mentioned flap being positioned in a plane substantially lower than the plane of the top wall panel, and a fold line extending medially of the side edges of said top and bottom wall panels and said end wall flaps, said holder being symmetrical with respect to said fold line.

3. A can holder for cans differing in height and diameter comprising a top wall panel wider at one end than at the other, a bottom wall panel having the same configuration as the top wall panel and oriented therewith, a pair of side wall panels connecting corresponding edges of the top and bottom wall panels together, flaps extending from opposite ends of the bottom wall panel and each foldable inwardly thereover to engage the inner portion of a can end flange adjacent to the bottom of a can positioned in the can holder, a flap extending from one end of the top wall panel and foldable inwardly thereunder engage the inner portion of a can end flange adjacent to the top of one of said cans, an end wall forming flap hinged to and extending downwardly from the opposite end of the top wall panel, said end wall forming flap having its lower edge terminating in predetermined spacing above said bottom wall panel, and a can flange engaging flap hinged to the lower edge of said end wall forming flap, the last mentioned flange engaging flap being foldable inwardly under said top wall panel to engage the can flange in a plane substantially lower than the plane of the top wall panel, and a flap attached to an upper portion of one of said side walls adjacent to said end wall forming flap and extending inwardly thereof and parallel thereto above the last said flange engaging flap.

4. A can holder for cans differing in height and diameter comprising a top wall panel wider at one end than at the other, a bottom wall panel having the same configuration as the top wall panel and oriented therewith, a pair of side wall panels connecting corresponding edges of the top and bottom wall panels together, flaps extending from opposite ends of the bottom wall panel and each foldable inwardly thereover to engage the inner portion of a flange adjacent to the bottom of a can positioned in the can holder, a flap extending from one end of the top wall panel and foldable inwardly thereunder to engage the inner portion of a can end flange adjacent to the top of one of said cans, an intermediate flap extending from and hinged to the opposite end of the top wall panel and foldable downwardly therefrom, said intermediate flap having a dimension measured in the direction of its extent from the

top wall end of less than the vertical height between said top and bottom wall panels, another flap foldable inwardly between said top and bottom wall panels and engageable with the inner portion of a flange adjacent to the top of said other can, the last mentioned flap being hinged to the intermediate flap in spaced relation to said top wall panel, whereby, when said intermediate flap is folded down and the last said flap is folded inwardly to engage the can flange, said last mentioned flap is positioned in a plane substantially lower than the plane of the top wall panel and the fold line extending medially through the last mentioned flap, the top wall panel and the flaps extending from opposite ends thereof, and another fold line extending medially through the bottom wall panel and the flaps extending from opposite ends thereof, whereby the can holder may be folded flat for shipping purposes.

5. A can holder adapted to hold cans of different heights comprising top and bottom wall panels connected by a pair of side wall panels, flaps extending from opposite ends of the bottom wall panel and each foldable inwardly thereover to engage the inner portion of a can end flange adjacent to the bottom of a can positioned in the can holder, a flap extending from one end of the top wall panel and foldable inwardly thereunder to engage the inner portion of a flange adjacent to the top of one of said cans, an intermediate flap extending from and hinged to the opposite end of the top wall panel and foldable downwardly therefrom, said intermediate flap having a dimension measured in the direction of its extent from the top wall end of less than the vertical height between said top and bottom wall panels, another flap foldable inwardly between said top and bottom wall panels and engageable with the inner portion of a flange adjacent to the top of said other can, the last mentioned flap being hinged to the said intermediate flap, whereby, when said intermediate flap is folded down and the last said flap is folded inwardly to engage the can flange, said last mentioned flap is positioned in a plane substantially lower than the plane of the top wall panel, and reinforcing flaps extending from corresponding upper edge portions of the side wall panels adjacent to said intermediate flap and foldable inwardly into juxtaposition with the said intermediate flap.

6. A can holder adapted to hold cans of different heights comprising top and bottom wall panels connected by a pair of side wall panels, flaps extending from opposite ends of the bottom wall panel and each foldable inwardly thereover to engage the inner portion of a can flange adjacent to the bottom of a can positioned in the can holder, a flap extending from one end of the top wall panel and foldable inwardly thereunder to engage the inner portion of a can flange adjacent to the top of one of said cans, an intermediate flap extending from the opposite end of the top wall panel and hinged thereto, another flap engageable with the inner portion of a flange adjacent to the top of said other can, the last mentioned flap being hinged to the intermediate flap along an axis substantially parallel to and spaced from the hinge axis of said intermediate flap and foldable inwardly between said top and bottom wall panels, whereby the last mentioned flap, when folded inwardly to engage the can flange, is positioned in a plane substantially lower than the plane of the top wall panel and above the bottom wall panel, a reinforcing flap extending from an upper portion of an end edge of a side wall panel adjacent to said intermediate flap and foldable inwardly across the end of said holder into juxtaposition with the said intermediate flap, and a tab connected with and foldable inwardly from one of the sides of the said last mentioned flap for engagement with the inner surface of the said reinforcing flap to hold it in juxtaposition with respect to the said intermediate flap.

flap engageable with the inner portion of a flange adjacent the top of said other can, the last mentioned flap being hinged to the intermediate flap along an axis substantially parallel to and spaced from the hinge axis of said intermediate flap and foldable inwardly between said top and bottom wall panels, whereby the last mentioned flap, when folded inwardly to engage the can flange, is positioned in a plane substantially lower than the plane of the top wall panel and above the bottom wall panel, a reinforcing flap extending from an upper portion of an end edge of a side wall panel adjacent to said intermediate flap and foldable inwardly across the end of said holder into juxtaposition with the said intermediate flap, and a tab connected with and foldable inwardly from one of the sides of the said last mentioned flap for engagement with the inner surface of the said reinforcing flap to hold it in juxtaposition with respect to the said intermediate flap.

7. A can holder adapted to hold cans of different heights comprising top and bottom wall panels connected by a pair of side wall panels, flaps extending from opposite ends of the bottom wall panel and each foldable inwardly thereover to engage the inner portion of a can flange adjacent to the bottom of a can positioned in the can holder, a flap extending from one end of the top wall panel and foldable inwardly thereunder to engage the inner portion of a can flange adjacent to the top of one of said cans, an intermediate flap extending from the opposite end of the top wall panel and hinged thereto, another flap engageable with the inner portion of a flange adjacent to the top of said other can, the last mentioned flap being hinged to the intermediate flap along an axis substantially parallel to and spaced from the hinge axis of said intermediate flap and foldable inwardly between said top and bottom wall panels, whereby the last mentioned flap, when folded inwardly to engage the can flange, is positioned in a plane substantially lower than the plane of the top wall panel and above the bottom wall panel, reinforcing flaps extending from corresponding edges of the side wall panels and foldable inwardly into juxtaposition with the said intermediate flap, and a pair of tabs connected with and foldable inwardly from opposite sides of the said last mentioned flap for engagement with the inner surface of the one of said reinforcing flaps to hold it in juxtaposition with respect to the said intermediate flap.
